UNITED STATES PATENT OFFICE.

HENRY H. BAKER, JR., OF BUFFALO, NEW YORK, ASSIGNOR TO WILLIAM H. PENSEYRES AND CHARLES HABERER, OF SAME PLACE.

DESIGN FOR A BICYCLE-FRAME.

SPECIFICATION forming part of Design No. 30,970, dated June 6, 1899.

Application filed May 5, 1898. Serial No. 679,854. Term of patent 14 years.

To all whom it may concern:

Be it known that I, HENRY H. BAKER, Jr., a citizen of the United States, residing at Buffalo, in the county of Erie, in the State of New York, have invented and produced a new and original Design for Velocipede-Frames, of which the following is a specification, reference being had to the accompanying drawings, forming a part thereof.

10 This invention relates to the configuration of velocipede or bicycle frames.

In the accompanying drawings, Figure 1 is a side elevation of a bicycle-frame embodying my design, the member of the lower rear fork 15 on the opposite or off side of the frame being omitted for the sake of clearness. Fig. 2 is a perspective view of the frame. Fig. 3 is a cross-section in line 33, Fig. 1, on an enlarged scale.

20 Like letters of reference refer to like parts in the several figures.

The leading feature of my design consists of a bicycle-frame having a front enlargement or casing arranged at one end of the crank-shaft hanger, a smaller rear enlargement or casing arranged at the lower end of the rear-wheel fork on the same side of the frame as the front enlargement, and a pair of longitudinal frame members arranged one above the 25 other and connecting the upper and lower portions of said front and rear enlargements and gradually increasing in depth toward said front enlargement.

30 A is the steering-head of the bicycle-frame; B, the cylindrical crank-shaft hanger or bracket; C, the inclined lower member extending from the lower portion of the steering-head to the hanger; D, the saddle-post extending upwardly from the hanger, and E the 40 upper or reach member connecting the upper portion of the steering-head with the upper portion of the saddle-post.

45 F F' are the members of the rear-wheel fork, which extend downwardly and rearwardly from the upper portion of the saddle-post, and G is the single left-hand member of the lower rear fork, which extends from the rear side of the hanger to the lower end of the left-hand member of the upper rear fork.

II is the upright enlargement or casing, 50 which is arranged at one end of the hanger, usually the right-hand end, and which has a convex or substantially semicircular front edge.

I is an upright casing or enlargement arranged at the lower end of the right-hand member F of the upper rear fork and having a convex or substantially semicircular rear edge.

h is an opening arranged axially in the front 60 enlargement or casing II, and h' an annular rib or bead arranged on the outer face of the casing concentrically with the opening h.

i is a longitudinal slot arranged centrally in the rear enlargement I. 65

J J' represent two longitudinal frame members which connect the front and rear enlargements II I and which are arranged one above the other on opposite sides of the plane of the single left-hand member G of the lower rear 70 fork. The members J J' taper rearwardly, or, in other words, gradually increase in depth toward the front enlargement, as shown in Figs. 1 and 2, and they are vertically elongated or oblong in cross-section, with 75 their greater axis or dimension in a vertical plane, as most clearly shown in Fig. 3. The upper edge of the upper member J is arranged tangentially to the upper side of the front and rear enlargements, while the lower edge of 80 the lower member J' is approximately tangential to the lower side of the said enlargements and bulged downward slightly adjacent to the latter, as shown at j j', giving these frame members the appearance of merging 85 into the enlargements.

What I claim is—

The design for a bicycle-frame, substantially as herein shown and described.

Witness my hand this 21st day of April, 90 1898.

HENRY H. BAKER, JR.
